UNITED STATES PATENT OFFICE.

SAMUEL THOMAS THORPE, OF BRISTOL, CONNECTICUT, ASSIGNOR TO THE HORTON MANUFACTURING COMPANY, OF BRISTOL, CONNECTICUT, A CORPORATION OF CONNECTICUT.

FISHLINE-REEL.

1,337,857.

Specification of Letters Patent. Patented Apr. 20, 1920.

Application filed October 17, 1919. Serial No. 331,441.

To all whom it may concern:

Be it known that I, SAMUEL THOMAS THORPE, a citizen of the United States, residing at Bristol, in the county of Hartford and State of Connecticut, have invented 5 certain new and useful Improvements in Fishline-Reels; and I do hereby declare the following to be a full, clear, and exact description of the same, reference being 10 had to the accompanying drawings, forming part of this specification.

This invention relates to fish-line reels, and more especially to that type of such reels in which provision is made for 15 restricting the free run of the spool and line, the mechanism for accomplishing this result being commonly called a drag. The objects of the invention are to provide an exceedingly simple drag mechanism suscep- 20 tible of accurate and minute adjustment to afford the desired resistance and which may be adjusted to set positions with a minimum effort and attention on the part of the fisherman and without danger of the 25 adjustment being accidentally changed.

In the accompanying drawings,—

Figure 1 is a view of a reel embodying the present improvements.

Fig. 2 is a sectional view showing the drag 30 mechanism, this view being on an enlarged scale to illustrate more clearly the internal construction.

Fig. 3 is an elevation looking at the inner side of the drag and handle head of the 35 reel.

Fig. 4 is a sectional detail.

Except as hereinafter pointed out, the general construction of the reel may conform to known or preferred practice and 40 hence the invention is shown embodied in a conventional reel embodying a frame A having heads B and C, and in which a winding spool D is journaled and adapted to be rotated through suitable gearing from a 45 handle E journaled in the head B or on the usual pin projecting from the inner plate B' of the head. The spool D embodies the usual concavo-convex spool heads, one of which D' is shown in section in Fig. 50 2, the concavo face being taken advantage of to form a graduated friction surface for coöperation with a friction member of the drag, as will presently appear.

The adjustable and adjusting part of the 55 drag is mounted in the head B and em-

bodies a carrier formed by an external knurled or roughened edge head F adapted to be turned with the fingers and thumb and bearing indices or numbers which by registering with a fixed index G indicate 60 the adjustment of the drag. The head F is preferably formed as an integral part of a generally cylindrical carrier body, one part of which f forms the journal in the head B and another part f' of which co- 65 operates with the retaining spring arms H to hold the parts against escape. Intermediate the parts f, f' is a recess or part of reduced diameter in which the arms H of the spring are located and the bottom of 70 the recess is in the form of a series of faces h (Fig. 4) with which the spring arms co- 75 operate to hold the drag in its angular positions of adjustment with the desired number in registry with the fixed index. The spring conveniently takes the form of a loop and is held by a screw I passing through the eye formed by the bend and into the head B.

The drag member F is provided with a 80 yielding friction member K adapted to bear against the concave face of the spool head D' and by the rotation of the member F the friction member is moved along the graduated friction face formed by the concave 85 or inclined face, and consequently bears with a greater or less pressure thereon. In the preferred construction illustrated the friction member K is in the form of a plunger mounted to slide in a hole or bore 90 formed in the member F parallel with but at one side or eccentric to the axis on which the member turns. The plunger is held advanced by a coil spring L surrounding the plunger behind a flange k and outward 95 movement is limited by an adjustable stop formed by the head of a set screw M against which the flange k comes to rest.

The rotation of the drag member F and the coöperation of the friction member K 100 with the graduated or inclined face of the spool head D', as well as the variable distance from the axis of the spool affords a frictional resistance to the turning of the spool, ranging from nothing, as when the member K is in the position shown in dotted lines in Fig. 2, to a maximum when in the position shown in full lines. This arrangement provides for a wide variation in the frictional resistance and the position may 105 110

be determined by the feel as well as by observation, for the spring arms H offer an intermittent resistance to changing the adjustment.

5 In addition to the adjustment just described, the set screw M may be adjusted to compensate for wear or to control the advance position of the plunger with extreme accuracy, thus meeting the requirements of the extremely fastidious fisherman.

10 The construction described constitutes a most effective anti-backlash reel which in use leaves the line taut from reel to bait at the end of the casting. It may be adjusted to suit any weight of bait while still maintaining the paramount advantage of maintaining a taut line when the cast bait strikes the water, thus saving many losses which ordinarily occur because of slack line 15 or a reel snarl at the instant after the bait drops into the water and is taken by the fish.

What I claim is:

1. A reel embodying a rotary spool, a 25 drag embodying a rotary carrier, and a friction member mounted thereon eccentrically with relation to its axis of rotation, and in position to frictionally coöperate with the reel at different distances from the 30 axis of rotation of the reel.

2. A reel embodying a rotary spool, a drag embodying a rotary carrier, a yielding friction member mounted thereon and movable thereby toward and from the axis of 35 rotation of the spool and into and out of engagement with the spool.

3. A reel embodying a rotary spool having a head with a surface inclined with respect to the axis of rotation, a drag embodying a carrier movable about an axis, a yielding friction member moved thereby, and while in engagement with the inclined surface on the spool in a direction toward and 40

from the axis of the spool to effect a variable resistance to the rotation of the spool. 45

4. A reel embodying a spool having a concavo-convex head, a drag embodying a rotary carrier, a spring-pressed plunger forming a friction member mounted in the carrier parallel with but to one side of the 50 axis of the latter and in position to coöperate with the convex face of the spool head to frictionally resist rotation of the spool.

5. In a fish-line reel embodying a spool having a concavo-convex head and a drag 55 embodying a rotary carrier, a spring-pressed plunger mounted in the carrier in position to engage the spool head, and an adjustable stop for limiting the advanced position of the plunger.

6. A reel comprising a frame, a removable head on the frame, a spool journaled in the frame, in combination with a drag embodying a carrier journaled in the head, means for yieldingly holding the carrier 65 in the angular position to which adjusted, and a friction member mounted on the carrier and movable thereby into and out of engagement with the spool at greater or less distances from the axis of rotation of the 70 latter.

7. A reel comprising a frame, a head on the frame, a spool journaled in the frame, in combination with a drag embodying a headed carrier having a cylindrical body 75 journaled in the reel frame and having an intermediate portion of reduced diameter and irregular contour, a retaining spring on the reel head and having arms located in the reduced portion of the carrier whereby 80 the latter is held in position, and a spool-engaging friction member moved by the rotation of the carrier to increase or decrease the resistance to the rotation of the spool.

SAMUEL THOMAS THORPE.
